SURGICAL APPLIANCE

Robert R. Norwood, Mineral Wells, Tex.

Application September 21, 1934, Serial No. 744,974

1 Claim. (Cl. 128—255)

This invention aims to provide a novel means for retaining and healing a replaced anal protrusion, for stopping internal hemorrhage adjacent to the anus, for treating prostatic and other disorders wherein the application of heat is indicated, and for other and similar purposes, which will suggest themselves readily to doctors of physic or surgery. A further object of the invention is to provide novel means for distending, filling and emptying a resilient sack which forms part of the device. Another object of the invention is to provide novel means whereby an outlet for gas and fecal matter is available, during the time that the instrument hereinafter explained is in place and in use. The device is characterized, further, by useful and patentably novel structural features which will be made manifest hereinafter.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

The drawing shows a satisfactory material embodiment of the invention, and in this drawing,

Fig. 1 is a longitudinal section, parts being in elevation;

Fig. 2 is a side elevation wherein sundry parts are broken away or shown in section;

Fig. 3 is a transverse section on the line 3—3 of Fig. 1.

Saving as otherwise specified, the device forming the subject matter of this application is made of metal, or some other substance having the necessary rigidity and capable of being maintained in a sterile condition. The instrument embodies a stem, which, as a whole, is marked by the numeral 1. The stem 1 may comprise an outer tube 2, of flattened or approximately elliptical cross section. A base plate 3 is secured to one end of the outer tube 2. The base plate 3 preferably is of elliptical outline (Fig. 3), and is 50 concavo-convex from side to side (Fig. 2). At its distal end, the outer tube 2 has a thickened head 4, which outstands a little beyond the periphery of the tube 2. An inner tube 5, preferably of circular cross section, is located within the outer tube 2 and is connected, as shown at 6, to the

sides of the tube 2. The stem 1, as to detailed structure, might be made otherwise than as described. The bore 7 of the inner tube 5 forms a straight drainage conduit, the said tube being extended backwardly, as shown at 17, beyond 5 the base plate 3 (Fig. 1).

The inner tube 5 is mounted in and extends forwardly a little way beyond the head 4 of the outer tube 2, as shown at 23. The space between the inner tube 5 and one side of the outer tube 10 2 (Fig. 3) constitutes an inlet conduit 8. The space between the inner tube 5 and the opposite side of the outer tube 2 constitutes an outlet conduit 9. A short length 10 of rigid pipe is secured to the basal end of the outer tube 2 and 15 constitutes a continuation of the inlet conduit 8. A valve 11, under the control of an operator, is assembled with the pipe 10, and a piece of flexible tubing 12, of any desired length, may be connected to the valve 11. A short length 14 of 20 rigid pipe is secured to the basal end of the outer tube 2 and constitutes a continuation of the outlet conduit 9. A valve 15, under the control of an operator, is assembled with the pipe 14, and a piece of flexible tubing 16, of any desired length, 25 may be connected to the valve 15. The pipes 10 and 14 diverge lengthwise of the base plate 3 (Fig. 1), and the end 17 of the inner tube 5 is located between them. The end 17 of the inner tube 5 is provided with a valve 18, under the control of an 30 operator, and to the valve 18 a length 19 of tubing may be connected. The parts 14, 17 and 10 are disposed to the rear of the base plate 3.

The numeral 20 designates a resilient sack, preferably made of rubber, and pear-shaped generally speaking. In the distal or wider end of the sack 20 there is an opening 21. A washer 22 of cloth of the like is placed about the projecting end 23 of the inner tube 5 and rests against the head 4 of the outer tube 2. The open, projecting end 23 of the inner tube 5 is thrust through the opening 21 in the sack 20, the wider end of the sack being in contact with the washer 22. A washer 24, of cloth or the like, is placed about 45 the end 23 of the inner tube 5 and engages the outer surface of the sack 20. A rigid washer 25 is placed on the end 23 of the inner tube 5 and engages the flexible washer 24. Finally, a nut 26 is threaded on the end 23 of the inner tube 5 and 50 engages the washer 25. The wider end of the sack 20 thus is bound against the head 4 of the outer tube 2, but there is no tearing of the sack 20, when the nut 26 is tightened, the flexible washers 22 and 24 preventing such a contingency. 55

The sack 20 may be removed readily for sterilization.

The narrow end of the sack 20 surrounds the outer tube 2, close to the base plate 3. It is preferable, however, to interpose a tubular grip and guard 27 between the neck of the sack 20 and the outer tube 2. The part 27 may be a length of adhesive tape, and is called a grip because it enhances the hold of the neck of the sack 20 on the tube 2, the part 27 being called a guard because it has an office in preventing heat in the stem 1 from finding its way outwardly, and making the appliance uncomfortably hot for the patient. The outward-conducting of the heat, however, is limited more particularly by an external shield 28, disposed about the reduced end or neck of the sack 20. The shield 28 may be simply a length of surgeon's gauze, wound about the neck of the sack 20. The construction is such that neither the base plate 3 nor the inner end of the tube 2 will cause the patient discomfort, it being well known that anal and buttock parts are somewhat sensitive to heat. The reduced end of the sack 20 may be secured in place in any desired way, for instance by binding a length of soft cord 29 about it tightly before the shield 28 is applied.

Near to its outer end, the outer tube 2 has openings 30, preferably in the form of transverse slits, the same constituting ports through which the fluid in the inlet conduit 8 can find its way into the sack 20. The fluid leaves the sack 20 through similar openings 31 in the tube 2 near to the inner end thereof, the last-mentioned openings constituting ports communicating with the outlet conduit 9.

Since this specification is addressed to a person skilled in the art, and since something must be accredited to the technique of the operator, all possible uses of the device need not be gone into with elaborate detail. The instrument may be used to retain a rectal protrusion, after the same has been replaced. It may be used to check hemorrhage in the rectal ampulla. It may be employed to apply heat, when heat treatment is indicated in connection with prostatic and similar glandular disorders.

After the instrument has been properly located, the sack 20 may be distended as much as desired, by introducing a fluid, such as air or water, into it; and if a heat treatment is indicated, hot water may be used. The fluid enters the sack 20 by way of the tubing 12, the pipe 10, the inlet con-

duit 8 and the ports 30. The fluid leaves the sack 20 by way of the ports 31, the outlet conduit 9, the pipe 14 and the tubing 16. After the sack 20 has been filled and distended, the valves 11 and 15 may be closed, and the instrument may be left in place as long as desired. If the operator wishes, he can obtain a continuous flow of the heating medium by leaving the valves 11 and 15 open. If he desires a continuous flow of the heating medium, coupled with a distention 10 of the sack 20, this can be accomplished by regulating the amount that the valves 11 and 15 are opened relatively to each other.

In treating pathological conditions to which the present invention ministers, it has been difficult heretofore to maintain heat and pressure for the necessary length of time, because when a high temperature, say 130 degrees F. is maintained, there is an irresistible impulse toward the evacuation of gas or fecal matter. When the device 20 herein disclosed is used, heat can be maintained as long as desired, and evacuation at the same time, may be permitted. All that the operator has to do is to open the valve 18, and then the inner tube 5 forms a passage for the escape of the 25 gas or ordure which is to be voided. There is, therefor, no reason why the instrument cannot remain in place long enough to reap the benefits of long-applied heat, or to effect, through a long-continued distention of the sack 20, a control of 30 rectal hemorrhage.

What is claimed is:

A device for treating rectal proctidria and prostatic and similar glandular disorders, and for controlling hemorrhage in the rectal ampulla, comprising a stem having a drainage conduit for fecal matter, extended through the stem from end to end, a resilient sack connected at its ends to the stem, the stem having an inlet conduit and an outlet conduit, each provided with a port communicating with the sack, and each embodying a tubular part extended out of the sack, the drainage conduit also comprising a tubular part extended out of the sack, a transverse base plate located between said tubular parts and the sack 45 and secured to the stem, a heat-retarding grip and guard disposed adjacent to the base plate and within the inner end of the sack, a heat-retarding shield disposed adjacent to the base plate and engaged outside the inner end of the 50 sack, and means for holding the inner end of the sack on the grip and guard.

ROBERT R. NORWOOD.
